(57) **CLAIM**

The ornamental design for a lace fabric, as shown and described.

DESCRIPTION

FIG. 1 is a front view of a lace fabric in accordance with the present invention.

FIG. 2 is a reference view of FIG. 1 with broken lines shown therein to indicate the area of detail view, FIG. 4.

FIG. 3 is a back side of FIG. 1; and,

FIG. 4 is an enlarged detail view of area 4 circumscribed by broken line in FIG. 2.

For clarity, the lace fabric is shown with a black background environment that forms no part of the claimed design. The broken lines in FIG. 2 and surrounding FIG. 4 indicate the area of the detail view and form no part of the claimed design.

1 Claim, 4 Drawing Sheets

FIG. 1

FIG. 2

FIG. 3

FIG. 4
